CARBURETOR

Frank D. Warburton, South Gate, Calif.

Application June 23, 1945, Serial No. 601,259

2 Claims. (Cl. 261—51)

1

This invention has to do with carburetors. It is among the aims of my invention to provide a carburetor of extremely simple and economical design which requires no float, which affords highly efficient admixture of the fuel with the incoming air stream, which requires a minimum of parts, and which eliminates the necessity of the frequent adjustments required in conventional carburetors.

Another shortcoming of conventional carburetors is the occurrence of "flat spots" at the commencement of acceleration due to the sudden opening of the butterfly valve before the fuel supply to the air passageway reaches adequate proportions.

It is therefore one of the principal aims of my present invention to provide a carburetor embodying means for preventing such "flat spots"—that is, my present invention provides a fuel supply booster which is automatically and momentarily operable at the commencement of acceleration.

Other objects will appear hereinafter.

For the purpose of making my invention better understood I shall now describe one of its preferred embodiments wherein I shall refer to the accompanying drawings, in which:

Fig. 1 is a medial vertical section;

Fig. 2 is a view partly in side elevation and partly in section as denoted by the line 2—2 of Fig. 1;

Fig. 3 is a view taken on line 3—3 of Fig. 1;

Fig. 4 is a view taken on line 4—4 of Fig. 1; and

Figs. 5 and 6 are enlarged fragmentary sections.

Referring to the drawings, the numeral 5 denotes the body, which has a round axial passageway 6 therethrough and is adapted to be secured to the intake of an internal combustion engine by means of the attaching flange 7. The medial portion of the body is of squared cross section while the upper and lower end portions are of round cross section. The passageway has a top end portion of relatively large diameter and a bottom end portion of reduced diameter, said portions intersecting each other in a beveled annular shoulder providing a throat 9.

The passageway is controlled by a butterfly valve 15 carried on the shaft 16 disposed transversely of and journaled in the body. The right-hand end of the shaft 16 has a collar carrying an arm 80, and a compression spring 20 on the opposite end of the shaft acts to rotate the shaft in one direction. The spring draws the shoulder

2

against the body only sufficiently to yieldably oppose free rotation of the shaft.

Also disposed transversely through and journaled in the body adjacent the throat 9, there is a shaft 25 having a shoulder 26 bearing against the body. On the opposite end of the shaft 25 there is a sleeve 28 which carries on its inner end a flange 30 whose inner face rotatably bears against the flat face 31 of the squared portion of the body. The sleeve 28 is axially slidable upon the shaft 25 but is held against rotation relative thereto by means of a collar 33 which is fixed to the shaft but has an ear 34 engaging in a slot 35 in the sleeve. A cap 37 is secured on the left-hand end of the shaft by a cap screw 39 and a compression spring 40 bears at one end against the cap and at its other end against the flange 30.

A cup 45 is secured to the body in sealing engagement therewith by cap screws extending through its attaching flange (not shown) and threadedly engaging in the body, the outer end of the cup having an opening 46 into which a fuel supply conduit 48 is threaded. The conduit 48 leads from a fuel source not shown so that in practice the cup 45 is maintained filled with fuel as by a fuel pump.

From the foregoing, it will be seen that the flange 30 is resiliently held against the body surface 31, through which surface fuel passageways 50, 51, 52 open and from which said fuel passageways lead to and discharge into the main body passageway 6.

Fuel passageway 50 is the idling fuel passage and communicates with passageway 6 as shown at 50a. Passageway 51 is the main fuel supply passageway communicating with the passageway 6 through a spray member 51a having a plurality of downwardly disposed orifices 51b. Passageway 52 is the booster fuel passage communicating with 40 the passageway 6 as shown at 52a.

As will be seen best in Fig. 4, the flange 30 has an eccentric peripheral portion 60 adapted, upon rotation of the sleeve, to gradually cover and uncover the main fuel passageway 51; has a peripheral projection 62 which is positioned to partially cover the idling fuel passage 50 when the carburetor is in idling position. The adjacent peripheral portion of the flange is circular, terminating in a shoulder 65 which is circumferentially spaced from the projection 62 so that limited rotational movement of the flange is possible without closing the idling fuel passage 50.

As best shown in Figs. 4 and 5, the booster passage 52 is normally maintained closed by a 55 spring-loaded ball valve 70 which is held against

escape from the passage by a plate 71 having an orifice slightly smaller than the maximum diameter portion of the ball.

To depress the ball and thus momentarily open the booster passageway 52, I provide a cam-like pawl 73 which is pivotally mounted on a boss 75 carried by flange 30. The pawl is urged against the stop pin 76, likewise carried by the boss, by a spring 77. Consequently, the pawl is free to swing about its pivotal mounting when the sleeve is rotated counterclockwise or in throttle-closing direction, but when the sleeve is rotated clockwise to open the throttle, it encounters the stop and thus depresses the ball by cam action as it passes thereover.

For rotating the shafts 16 and 25, an arm 80 is rotatably mounted on shaft 16, the outer end of the arm being pivotally connected to the conventional actuating link 81 at its outer end 80a. An arm 82 is fixed on shaft 25, the latter arm being operatively connected to arm 80 by means of a link 84 so that both arms 80, 82 swing in unison. In arm 80 there is an arcuate slot 85 disposed circumferentially of shaft 16 and fixed on the latter shaft there is a collar 86 carrying a pin 87 which projects into the slot for movement between the ends of the slot to permit a limited amount of lost motion. The purpose of this lost motion is explained as follows: In opening the throttle the shaft 25 is rotated relative to the shaft 16 until the pawl 73 engages the ball 70 to start opening of the passageway 52. Thus the butterfly valve does not commence its opening movement until the booster passage opening is commenced and booster fuel delivered to passageway 6. On the closing operation, the lost motion described permits the projection 62 to move into position partially closing the idling passageway after the butterfly valve has been closed and permits an adjustment such that the butterfly valve may be left slightly open.

The shaft 16 is adjustably limited in its closing movement by a stop screw 90 (see Figs. 2 and 3) threaded into boss 91 carried by the body, the inner end of the screw being positioned to engage a radial arm 92 carried by a collar 93 fixed on shaft 16. The extent of the closure of the idling passage by projection 62 may be regulated by the adjustable stop screw 94 threaded into an angled portion 80b of arm 80 for engagement with boss 91, which adjustment also determines the amount of movement of flange 30 after the butterfly valve is closed. Both stop screws 90 and 94 carry compression springs to lock them against vibrating out of set position.

Operation is as follows: To open the throttle, the actuating link 81 is moved to swing arm 80, which in turn initially rotates shaft 25 along until the pawl 73 engages ball 70. At this point the lost motion pin 87 engages an end of the arcuate slot 85 and thus further movement of link 81 causes the shafts 16, 25 to rotate in unison, resulting in the gradual opening of main fuel passage 51 by virtue of the eccentric peripheral portion 60 of the flange 30 as well as the closing of the idling passage 50. To close the throttle the link 81 is moved in the opposite direction, first causing the flange 30 to gradually close the main fuel passageway 51, simultaneously opening the idling bypass 50, and then moving the projection 62 into position partially closing the idling passage 50. Thus it will be observed that immediately prior to opening of the butterfly valve, a booster charge of fuel is momentarily discharged into the air passage 6

above the butterfly valve so that, upon opening the butterfly, there is an extra supply of fuel.

I claim:

- 5 1. In a carburetor, the combination of a body having an air passage therethrough and a fuel supply chamber, a first shaft journaled in the body and disposed transversely of the air passage adjacent the outlet end thereof, a butterfly valve carried by the shaft to control the air passage,
- 10 10 a second shaft journaled in the body and disposed transversely of the air passage between the inlet end thereof and the first-mentioned shaft, one end of the second shaft projecting into the fuel supply chamber through a side wall thereof, a main fuel feed port and a booster fuel feed port in the body, each opening at one end into the fuel supply chamber through said side wall and communicating at its other end with the air passage, a sleeve axially slidably mounted on the second shaft within the fuel supply chamber, means preventing rotation of the sleeve relative to the second shaft, a disc-like valve fixed on the inner end of the sleeve and rotatably bearing against said side wall in normal covering relationship to the main fuel feed port, said disc-like valve having an eccentric peripheral portion adapted upon rotation thereof to gradually open and close said main fuel feed port, means carried by the disc-like valve to control the booster fuel feed port, said means being operable in response to initial rotation of the disc-like valve in a direction which will open the main fuel feed port to momentarily open the booster fuel feed port, and means for rotating the shafts, said 20 30 35 last-named means having a lost motion connection to the first shaft and a fixed connection to the second shaft whereby to cause limited initial rotation of the disc-like valve before actuating the butterfly valve.
- 40 2. In a carburetor, the combination of a body having an air passage therethrough and a fuel supply chamber, a first shaft journaled in the body and disposed transversely of the air passage adjacent the outlet end thereof, a butterfly valve carried by the shaft to control the air passage, a second shaft journaled in the body and disposed transversely of the air passage between the inlet end thereof and the first-mentioned shaft, one end of the second shaft projecting into the fuel supply chamber through a side wall thereof, a main fuel feed port and a booster fuel feed port in the body, each opening at one end into the fuel supply chamber through said side wall and communicating at its other end with the air passage, a sleeve axially slidably mounted on the second shaft within the fuel supply chamber, means preventing rotation of the sleeve relative to the second shaft, a disc-like valve fixed on the inner end of the sleeve and rotatably bearing against said side wall in normal covering relationship to the main fuel feed port, said disc-like valve having an eccentric peripheral portion adapted upon rotation thereof to gradually open and close said main fuel feed port, a spring-loaded ball check valve normally closing the booster fuel feed port, pawl-like cam means swingably carried by the disc-like valve, said cam means being operable in response to initial rotation of the disc-like valve in a direction which will open the main fuel feed port to momentarily engage and move the ball check valve off its seat and being swingable in response to rotation of the disc-like valve in the reverse direction whereby to pass over the ball
- 50 55 60 65 70 75

check valve without moving it off its seat, and means for rotating the shafts, said last-named means having a lost motion connection to the first shaft and a fixed connection to the second shaft whereby to cause limited initial rotation of the disc-like valve before actuating the butterfly valve.
